UNITED STATES PATENT OFFICE.

JAMES ARTHUR SMITH, OF CHICAGO, ILLINOIS.

ATTACHMENT FOR SHOE STANDS.

1,412,200.

Specification of Letters Patent. Patented Apr. 11, 1922.

Application filed December 23, 1920. Serial No. 432,841.

To all whom it may concern:

Be it known that I, JAMES ARTHUR SMITH, a citizen of the United States, residing at Chicago, in the county of Cook and State of Illinois, have invented certain new and useful Improvements in Attachments for Shoe Stands; and I do declare the following to be a full, clear, and exact description of the invention, such as will enable others skilled in the art to which it appertains to make and use the same.

This invention relates to an improved attachment for shoe stands to permit the latter to be rotatably mounted so that the repairman can stand still and move the shoe to various positions instead of moving about the shoe itself as is ordinarily done.

Another feature and object of the invention is to connect the stand and attachment with the work bench so that in addition to having a rotary stand the latter will be at a convenient elevation to permit the repairman to stand up when working instead of sitting down in cramped positions as he ordinarily does.

Another object of the invention is to provide a novel and simple attachment of the class described the same being of such construction that it can be easily and readily placed in position on conventional types of stands and will permit the latter to rotate in a single direction. However, by reversing the position of the attachment, rotation in an opposite direction will be permitted.

A further object of the invention is to provide a simple attachment embodying a ratchet wheel surrounded by a ring, a pawl being struck out, or formed from a part of said ring.

A still further object of the invention is to provide a novel device for holding a shoe in position on the last.

The foregoing and other objects and advantages of the invention will become apparent during the course of the following description.

In the accompanying drawings forming a part of the specification and in which like numerals are employed to designate like parts throughout the same:

Figure 1 is a perspective view of a work bench constructed and arranged in accordance with my ideas, the shoe stand being mounted thereon, the attachment for rotatably mounting it being shown, and the novel shoe holding device being also shown.

Figure 2 is a top plan view, with the top face plate removed, of an attachment constructed in accordance with this invention.

Figure 3 is a central longitudinal sectional view taken on the plane of the line 3—3.

Figure 4 is a perspective view of one of the details of the attachment.

Figure 5 is a sectional view taken through the stand showing the novel shoe holding device connected thereto.

Figure 6 is a perspective view of the two-parts clamp of the shoe holding device.

Under ordinary circumstances, most shoemakers attach the shoe stand to the floor close to a stool upon which they sit while repairing the shoe. This stand is ordinarily stationary and in addition to the repairman becoming cramped from working under these undesirable conditions, he becomes very tired because he necessarily has to move about the shoe in order to obtain the most advantageous position for doing certain work. To overcome these circumstances, I contemplate employing a work bench 1 which when constructed in accordance with my ideas, includes upper and lower spaced horizontally disposed boards 2 and 3 respectively. In actual use, I suggest that the bench be placed over a stool or other support 4 which will act as a brace for the lower board 3. This brace, of course, need not be in the form of a stool. Formed in the upper board 2 at a point directly over the stool 4 is an opening 5 through which the upper end of a conventional shoe stand 6 projects, the latter being arranged in a vertical position between the boards 2 and 3, and the base thereof resting loosely on the lower board 3 at a point where the member 4 is connected to this board. With this arrangement, the shoemaker can stand up while working.

The attachment referred to, in its preferred form, comprises ratchet disk 7 provided with a central opening 8 of cross formation adapted to surround the similarly shaped stand 6. Surrounding the outer periphery of this disk 7 is a ring 9, this ring carrying a spring pressed dog or pawl 10 for coaction with the teeth of the ratchet disk so as to permit it to rotate in a single direction only. While it is not necessary, I find that it will be found advantageous from the manufacturers standpoint to form the dog 10 from the same material which constitutes a part of the ring 9. In other

words, a substantially wedge-shaped dog is cut out from the ring and is so cut at its inner end as to provide a dove-tail connection 11 with the ring as shown. Positioned 5 above and below and contacting the parts 7 and 9 are face plates 12 of ring-like formation. To retain the parts together, a rim 13 is employed and this rim surrounds the outer peripheries of the ring 9 and face 10 plates 12. If desired, the rim may be formed with an inwardly directed flange 14 on which the lower face plate may rest. As shown in the drawings, the attachment is secured to the upper board 2 of the work 15 bench around the opening 5, the stand 6 being connected with this through the medium of the opening 8. In order to connect the attachment with the bench, the face plates and ring are provided with vertically 20 aligned holes for passage of the fastening bolts 15. With the attachment in place, the shoemaker can rotate the stand to enable him to place the shoe in the most advantageous position for working on it. Consequently, instead of moving about the work 25 as is ordinarily done, he may stand still and move the work and he will thus be prevented from tiring in such a short time.

Since some shoes cannot be effectively fitted on the last without moving too loosely to permit the shoemaker to work advantageously, I have devised a simple attachment for effectively holding the shoe against undue movement. This attachment is shown 30 in Figures 5 and 6. By reference to these figures, it will be seen that it comprises a two-part clamp 16 for connection to the stand, a coiled spring 17, and a looped strap 18 to be placed on the shoe in the manner 35 illustrated or in any other convenient and desirable way.

From the foregoing description, it will be seen that under my ideas, a shoemaker will be enabled to work more easily than under 40 existing conditions. This is due to the fact that the employment of my improved work bench will position the work at a desirable elevation to enable the repairman to stand up while working. Furthermore, the work 45 can be easily and readily moved to various positions and it will be unnecessary to walk

from place to place about the work in order to obtain the most advantageous position. The work can be rotated in one single direction and can be moved to the desired degree. 55 Also, by using my improved holding device, the repairman will have free use of both hands and need not hold the shoe with one hand as ordinarily done. These and other advantageous features of the invention, have, 60 no doubt become apparent from the foregoing description and drawings.

Since probably the best results may be obtained with the construction and arrangement herein shown and described, this construction and arrangement is taken as the preferred embodiment of the invention. However, it is to be understood that various minor changes within the scope of the invention may be resorted to. 70

I claim:

1. In combination, a work bench including upper and lower spaced horizontal boards, a bracing member positioned beneath the lower board, the upper board having a hole formed therein directly over said bracing member, a shoe stand arranged in a vertical position between the boards and resting on the inner face of the lower board and extending through the hole in the upper board, and means secured on the last named board and surrounding said hole and connected with said stand for permitting rotation of the latter. 75

2. An attachment for rotatably mounting 80 shoe stands comprising a ratchet disk having a central hole of cross formation, a ring surrounding the disk, a pawl carried by said ring and engageable with the teeth of said disk, a pair of face plates of ring-like 85 formation positioned, one on top of said ring and disk and one beneath them, both of said plates being of the same diameter as the ring and the latter and plates being formed with vertically aligned attachment 90 holes, and a rim surrounding and connected to the ring and plates, being of a width equal to the combined thickness of the ring and plates. 95

In testimony whereof I have hereunto set my hand.

JAMES ARTHUR SMITH.
